UNITED STATES PATENT OFFICE

2,598,595

MIXING METHOD AND PACKAGE

Leo Peters, Evanston, Ill.

Application March 30, 1948, Serial No. 17,885

5 Claims. (Cl. 99—179)

1

This invention relates to the packaging of oleomargarine and to the coloring of the same. The invention is particularly useful in connection with the packaging of uncolored oleomargarine in such a manner as to permit its being colored by the consumer without removing the oleomargarine from the package.

Present day packages for uncolored oleomargarine are accompanied by separate devices or packets containing coloring material. When coloring material accompanies the package of uncolored oleomargarine, the problems and costs of packaging are much greater than when no coloring material accompanies the package. Such packages also can be somewhat unsightly after the coloring operation is completed if the housewife does not use all of the coloring material or if the coloring material itself dyes the wrapper.

An object of the present invention is to provide a package for uncolored oleomargarine without any accompanying color, yet which will enable the housewife to color the oleomargarine without removing the wrapper. A further object is to package oleomargarine in a flexible, sealed wrapper to which is attached a patch or strip of material, the character of which will permit easy passage for an injection needle, while at the same time will retard or prevent the egress of oleomargarine after the needle is withdrawn by the self-sealing of the hole made by the needle. A still further object is to provide a package for uncolored oleomargarine and means for injecting coloring material into the sealed, flexible package, which will enable the housewife to control precisely the amount of coloring she wishes to inject, while at the same time enabling the housewife to knead the oleomargarine in the coloring step without removing it from the package. Yet another object is to provide the housewife with a sealed package of uncolored oleomargarine and with means for injecting color into the oleomargarine at several places, thus facilitating the speed with which the oleomargarine may be colored in the kneading step. A still further object is to provide a package for uncolored oleomargarine in which the cost and labor of attaching coloring material is eliminated, while at the same time providing a sealed structure equipped with means for sealing an opening formed by an injecting needle to permit the thorough kneading of the oleomargarine without egress of oleomargarine during the kneading operation. Other specific objects and advantages will appear as the specification proceeds.

2

The invention is illustrated, in a single embodiment, by the accompanying drawing, in which—

Figure 1 is a perspective view of a package embodying my invention; Fig. 2, a plan view of an injection needle and pump which may be employed in conjunction with the package and in the practice of the method; and Fig. 3, an enlarged transverse sectional view showing the injection needle extended through the sealing patch of the wrapper.

In the illustration given, 10 designates a wrapper enclosing a body of oleomargarine 11. The wrapper 10 may be formed of translucent material, such as, for example, synthetic rubber, vinylite material, etc. I prefer to employ a material which is translucent so as to permit the housewife to see the progress of the coloring operation, while at the same time the wrapper should be flexible and strong enough to permit the kneading of the oleomargarine to be carried out without breaking the wrapper. Chlorinated rubber may be used. Thermoplastic materials, such as, cellulose acetate, vinyl acetate, vinyl chloride (copolymer), polytetrafluoroethylene polymer, and a large number of other well-known materials may be employed.

The wrapper 10 may be tubular and may be sealed at one end and then filled with oleomargarine, the other end being then sealed. If desired, the wrapper 10 may be in the form of a sheet and the edges thereof may be drawn about a cake of oleomargarine, and the abutting edges then sealed together to form a closed package. By employing some of the thermoplastic materials mentioned, the sealing may be effected by the application of heat, electric current, etc.

To the wrapper 10, and preferably prior to the time that it is filled with oleomargarine, I attach a patch 12 of self-sealing material. In the illustration given, the patch is formed of sponge rubber, which is attached to the wrapper 10 by rubber cement, or any other suitable means. I have found that excellent patches are provided by the sponge or foam rubber and also by rubber-like materials having a gummy or tacky interior. Rubber latex and synthetic plastic materials, which are well known for their self-sealing properties, may be employed for this purpose, and they may be secured by a rubber cement or other adhesive resilient cements, or by heat sealing, etc.

The patch 12 may be attached to the inside or to the outside of the wrapper, and it may cover a small portion or constitute all or any part of the

wrapper itself. It will be sufficient for the present purposes to illustrate the patch as applied to one side of the package.

Any means for injecting coloring material into the oleomargarine through the patch may be employed. In the illustration given, a conventional syringe 13 is shown equipped with a hollow needle 14, which is passed through the sponge rubber patch 12 and the wall of wrapper 10, as illustrated in Fig. 2. By this means, coloring material in liquid, powder, or other fluid form may be introduced through the needle and into the interior of the oleomargarine. The needle permits the injection of coloring material at points extending transversely of the package and also in the distant end portions of the package, if desired. This is accomplished merely by swinging the needle to the right or to the left through the single opening shown. If desired, the package may be equipped with several patches to permit injection at various points about the package. After the desired amount of coloring material has been introduced deeply into the interior of the oleomargarine, the needle 14 is withdrawn and the opening formed thereby is sealed by the foam latex or sponge rubber patch 12. The package may then be manipulated in a kneading operation to quickly mix the coloring material with the oleomargarine. By reason of the wide distribution of coloring material in the oleomargarine body, the mixing step requires little time to bring about the uniform coloring of the oleomargarine mass.

By the method described, it is found that the coloring material is evenly distributed and that there is no tendency for a spot of coloring material, unmixed with oleomargarine, to be present at any particular point about the wrapper. Instead, all of the coloring material is mixed with the oleomargarine.

After the kneading operation described, the package is again shaped by pressing it along the sides and ends and is preferably restored to the original box container in which it was purchased. The material forms an even rectangular block upon being restored to the refrigerator within such container. Later, as the oleomargarine is kneaded, the package may be cut through by a knife and the portion of the severed wrapper removed as its contents are placed upon a dish.

In the coloring material injecting step, it will be understood that any pump and needle structure may be employed. A hollow needle fitted to a plunger pump of any type will be sufficient for injecting the coloring material through the patch and into the oleomargarine interior.

While, in the foregoing description, I have set forth a package structure and method for coloring in considerable detail for the purpose of illustrating the invention, it will be understood that such details of structure and method steps may be modified widely by those skilled in the art without departing from the spirit of my invention.

I claim:

1. A mixing package comprising a wrapper of flexible translucent material adapted to be sealed about a body which is to be kneaded, a body of oleomargarine within said wrapper, the wall of said wrapper being sealed to itself to form a continuous unbroken wall about said body, and a

flexible self-sealing patch of liquid-tight material secured to the outer surface of said wrapper wall, said patch forming a liquid-tight seal after the withdrawal of a hollow needle which has been inserted therethrough.

2. A mixing package comprising a transparent flexible wrapper adapted to be sealed about a body which is to be kneaded while within the wrapper, a body of oleomargarine in said wrapper, the wall of said wrapper being sealed to itself to form a continuous unbroken wall about said body, and a flexible self-sealing patch secured to the outer surface of the wrapper wall and flexing with said wrapper in the kneading of the contents of the package.

3. A mixing package comprising a wrapper of flexible translucent material adapted to be sealed about a body of oleomargarine which is to be kneaded while within said package, a body of oleomargarine in said wrapper, the wall of said wrapper being sealed to itself to form a continuous unbroken wall about said body, and a liquid-tight self-sealing patch sealed to a wall of said package and adapted to close an opening, formed by a hollow needle for the injection of coloring material into the sealed package, against the egress of the contents of the package, said patch flexing freely in the manipulation of the walls of the package for the kneading of the contents thereof.

4. In a mixing method, the steps of enclosing a body of oleomargarine within a flexible translucent wrapper, sealing the wrapper about the material, securing a self-sealing patch to the wall of the wrapper, introducing coloring material to be mixed with the oleomargarine in the sealed wrapper and through a hollow needle passing through said patch, withdrawing the needle after the introduction of said coloring material into the package, and then kneading the oleomargarine and coloring material within the package to mix the same.

5. In a method for mixing oleomargarine and coloring material therefor, the steps of securing to a flexible transparent wrapper a flexible patch of self-sealing material, enclosing a body of oleomargarine within the wrapper, sealing the wrapper about the oleomargarine, passing a hollow needle through said patch and into the oleomargarine within the package, introducing through the hollow needle coloring material to be mixed with the oleomargarine, withdrawing the needle to effect sealing of the wrapper, and then kneading the oleomargarine and coloring material within the package while enclosed in the sealed wrapper.
